UNITED STATES PATENT OFFICE.

EDMUND F. HARTSHORN, OF NEWARK, NEW JERSEY, ASSIGNOR TO STEWART HARTSHORN COMPANY, OF EAST NEWARK, NEW JERSEY, A CORPORATION OF NEW JERSEY.

SHADE-ROLLER.

1,093,931.

Specification of Letters Patent. Patented Apr. 21, 1914.

Application filed July 1, 1912. Serial No. 706,880.

To all whom it may concern:

Be it known that I, EDMUND F. HARTSHORN, a citizen of the United States, residing in Newark, county of Essex, State of New Jersey, have invented a new and useful Shade-Roller.

The object I have in view is the production of a shade roller for heavy work.

This invention relates particularly to shade rollers for use upon awnings, large curtains, and similar structures. Heretofore, such rollers have been reinforced by a solid round reinforcement. When the roller is as much as four inches in diameter, the reinforcement must be made of a large and expensive piece of wood. According to my invention, I utilize relatively cheap material and produce a roller possessing great rigidity and strength, at the same time being light in weight. Another objection to a roller made of a single piece of wood, is that seasoned material must be employed, otherwise the roller will warp. Even when the material is carefully selected, in use,—particularly for awnings outside of buildings, the roller is apt to warp and thus lose its shape.

These and further objects will more fully appear from the following specification and accompanying drawings, considered together or separately.

In the drawings, Figure 1 is a longitudinal sectional view of a roller embodying my invention. Fig. 2 is a section on the line 2—2 of Fig. 1. Figs. 3, 4, 5 and 6 are sectional views of modifications.

In all of the views, like parts are designated by the same reference characters.

The preferred roller comprises a shell 1. This shell is made of sheet metal, preferably tin. It is the full length of the roller; that is to say,—it extends from end to end of the roller. Preferably it is made of a single piece, rolled to shape, with a lapped joint, as shown in Figs. 2, 3, 4 and 5. The method of joining it, however, is immaterial. A large, long roller formed of tin would lack the necessary rigidity, consequently, I insert within the shell a reinforcing core 2. This core preferably extends from one end of the roller to a position close to the other end, the space between the core and the other end of the roller being occupied by the spin-

dle 4 and spring 5. In Fig. 1, the usual spear 3, spindle 4, and spring 5 are shown. On the other end of the roller is the usual end pin 6. This pin is shown as attached to a plate 7, and this plate is secured by screws 8 to the reinforcing core 2. This forms a very cheap fitting for this end of the roller. The core is provided with a bearing 9, for the end of the spindle. The preferred form of core is shown in Fig. 2. This comprises a center member 10. This member may be satisfactorily made of wood. A piece of board, of commercial thickness, may be employed. The edges are rounded to shape, so as to snugly fit within the shell. Wing members 11, 11, are secured on each side of the center member. Suitable fastenings 12, such as nails, secure the parts together. The edges of the wing members are rounded so as to make a close fit with the shell. This structure is very simple and cheap of manufacture; and it is much lighter than a solid wooden roller. Being formed of cheap stuff, it can be built with a minimum of cost. A great advantage lies in the fact that the wing members, when they warp, will be counteracted by the center member, and the center member, when it warps, will be counteracted by the wing members.

Instead of the fastenings 12, the wing members may be provided with ribs 13, shown in Fig. 3. The parts may be further secured together by glue.

The arrangement shown in Fig. 4 embodies four strips, 14, suitably secured together by fastenings, such as nails.

Instead of employing a wooden core, a metal core, 15, shown in Fig. 5, may be employed. The core preferably extends from the pin of the roller to the spear, and is preferably made in a single piece, as shown. It may be made in a number of sections, however, suitably disposed within the shell so as to strengthen the latter and prevent it from collapsing. This is shown in Fig. 6.

In accordance with the provisions of the patent statutes, I have described the principle of my invention, together with the apparatus which I now consider to represent the best embodiment thereof; but I desire to have it understood that the apparatus shown is merely illustrative and that the invention can be carried out in other ways.

Having now described my invention, what I claim as new and desire to secure by Letters Patent, is:—

1. A spring shade roller having a sheet metal shell of the length of the roller, a spindle within the shell, a skeleton core extending through the greater part of the length of the shell, said core carrying a bearing for the spindle.
2. A spring shade roller having a sheet metal shell of the length of the roller, a spindle having a bearing in one end of the shell, a reinforced skeleton core extending from the spindle to the other end of the shell, said spindle having a bearing in the core.
3. A spring shade roller having a sheet metal shell of the length of the roller, a spindle having a bearing in one end of the

shell, a reinforcing skeleton core within the shell, said core being formed of strips of wood secured together in such a manner as to present numerous points of contact extending longitudinally of the shell, and a bearing for the spindle in the core.

4. A spring shade roller having a sheet metal shell of the length of the roller, a spindle within the shell, a core contacting with the shell at diametrical intervals, the points of contact extending longitudinally of the shell, said core carrying a bearing for the spindle.

This specification signed and witnessed this 20th day of June, 1912.

EDMUND F. HARTSHORN.
